UNITED STATES PATENT OFFICE.

HARRY B. WOLPER, OF CHICAGO, ILLINOIS, ASSIGNOR TO NIGHTINGALE MANUFACTURING COMPANY, OF CHICAGO, ILLINOIS, A CORPORATION OF ILLINOIS.

DESIGN FOR A TALKING-MACHINE CABINET.

55,227.

Specification for Design.

Patented May 18, 1920.

Application filed March 5, 1920. Serial No. 363,580. Term of patent 14 years.

To all whom it may concern:

Be it known that I, HARRY B. WOLPER, a citizen of the United States, residing at Chicago, in the county of Cook and State of Illinois, have invented a new, original, and ornamental Design for a Talking-Machine Cabinet, of which the following is a specification, reference being had to the accompanying drawing, forming a part thereof.

The figure is a perspective elevational view of a talking machine cabinet showing my new design.

I claim:

The ornamental design for a talking machine cabinet, as shown.

HARRY B. WOLPER.
